LOADING DEVICE FOR REVOLVERS

Joseph E. Miano, Larchmont, N. Y.

Application August 25, 1932. Serial No. 630,362

9 Claims. (Cl. 42—89)

This invention relates to loading devices for revolvers and the like and has for one of its objects the provision of a device of this character provided with a magazine having a plurality of cartridge chambers, together with means for normally maintaining the cartridges in the magazine, the said means being operable to release the cartridges to permit all of them to simultaneously drop into the revolver barrel.

Another object of the invention is to provide a loading device of this character adapted to contain a plurality of charges of ammunition one above the other, together with means for separating the said charges, the said means being adapted to be operated to permit the upper charge to drop down after the lower charge has been used up.

A further object of the invention is to provide such a device which may be operated by pressure to release the charge when loading the revolver.

A still further object of the invention is to provide a device of this character which is equally adapted to be used with revolvers in which the barrel is swung outwardly for reloading, as with revolvers of the break type.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawing, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawing, in which

Figure 1 is a side view in elevation of a revolver with the barrel thereof swung out in loading position and my improved loading device in position for reloading same.

Figure 2 is a perspective view of the device. Figure 3 is a longitudinal sectional view thereof.

Figure 4 is a horizontal sectional view taken on line 4—4 Fig. 3.

Figure 5 is a bottom end view thereof.

Figure 6 is a top plan view of the shell showing the separating ring in position and

Figure 7 is a perspective view of one half of the said ring.

Referring to the drawing in detail 10 indicates my improved loading device, which as illustrated comprises a shell 11 having a central tube 12 and a nest of six tubes 13 equidistantly spaced about the said central tube 12 and secured thereto and to the shell 11 as by soldering or spot welding. If desired, all of the tubes as well as the outer shell may be made of one integral die casting.

Located within the central tube 12 and rotatably mounted therein is a hollow cylinder 14 which is provided at the bottom thereof with a six pointed wheel 15 having radially extending tines or prongs 16 which normally extend into the path of the bores in the tubes 13. Slidingly mounted within the cylinder 14 there is a rod 17 having a lower cylindrical portion 18 and an upper reduced square shank 19 which is twisted as at 20 and extends through a clearance opening 21 in the top wall of the cylinder 14 and a square opening 22 near the top of the central tube 12. A pin 25 in the cylinder 14 extends into a keyway 26 in the portion 18 of the rod 17. A coiled spring 27 exerts a tension between the cylinder 14 and rod 17 and the said rod is prevented from dropping out of place by means of a pin 28 passing through the upper portion of the shank 19 and bears against the upper wall 29 of the tube 12.

The central tube 14 may be provided with an extension 30 having an exterior thread 31 to which is screw threadedly secured a cap 32 which closes the device at the top thereof.

The body or shell 11 as well as the tubes 13 are horizontally slotted intermediate their ends as at 33 and 34 respectively to accommodate the prongs or tines 35 of a ring 36 made of two similar halves 37 and united together at their ends 38 as by spot welding or soldering when in place about the shell 11. A spring 39 tends to keep the ring so that the prongs 35 are centrally positioned with respect to the tubes or openings 13. It will be understood that these prongs 35 divide the magazine into upper and lower ammunition or cartridge chambers 40 and 41. The cartridges

in the lower chambers normally resting on the prongs 16 of the cylinder 14 and the cartridges in the upper compartments resting on the prongs 35 of the ring 36.

5. By referring to Fig. 1 it will be seen that in loading or reloading the revolver 45, the barrel 46 thereof is first swung to the side after removing the pin upon which it normally revolves the tapered point 47 of the rod 17 is then inserted 10 into the central bore 48 of the ejector ratchet and the device is then pressed downwardly. This pressure pushes the rod 17 upwardly against the tension of the spring 27 and it is given a partial rotation of approximately 15 degrees. Due to 15 the fact that the pin 25 in the lower portion of the cylinder 14 is in engagement with the keyway 26, the said cylinder and its prongs 16 will be rotated with the rod and assume the position shown in Figure 5, thus permitting the cartridges 20 in the chambers 41 to drop into the barrel chambers. When the pressure is released the parts will again return to their normal position.

By rotating the ring 36 in the direction of the arrow Figure 4 until the prongs 35 assume the 25 dot and dash position, the cartridges in the upper compartments 40 will drop down into the lower compartments 41 and upon releasing the said ring 36 the spring 39 will carry same back to 30 normal position against the opposite end of the slots 33 and 34.

It is to be understood that the upper compartments 40 as well as the ring 36 may be omitted in devices of this character where only single charge carrying magazines are required. By removing the cap 32 the loading device may again 35 be filled up with ammunition.

While I have shown my device as applied to a revolver having a swingable barrel, I desire it understood that the device is just as adaptable for 40 use with a revolver of the break type, that is where the muzzle is pivoted and carries the barrel with it when it is moved about the said pivot.

From the foregoing it will be seen that I have provided a loading or reloading device for revolvers carrying a plurality of cartridges, the 45 said device loading all the revolver barrel compartments simultaneously thus saving a great deal of time when such time is often very precious.

Having described my invention what I claim 50 as new and desire to secure by Letters Patent is:

1. A loading device for revolvers, comprising a body having an ammunition carrying compartment therein, a turnably mounted ammunition supporting member in the body, and yieldable means in operative engagement with the said member adapted to move same out of the path of the ammunition when pressure is applied to the said means.

2. A loading device for revolvers, comprising a body having a plurality of cartridge carrying compartments, arranged in circular formation therein, a turnable member centrally located in the said body with respect to the said compartments, prongs on the said member extending into the path of the cartridge chambers to normally support the cartridges, and yieldable means in operative engagement with the said member to move same and carry the prongs out of the path of the cartridges, when pressure is applied to said means.

3. A loading device for revolvers, comprising a body having a rectangular opening centrally located at the top thereof, a cylindrical chamber below the said opening, a plurality of cartridge carrying compartments arranged radially with

respect to the said opening and chamber, a cylinder movably mounted in the chamber, prongs extending from the said cylinder extending into the path of the compartments for normally supporting the cartridges, a spring pressed rod slidably mounted in the cylinder, a rectangular and twisted shank at one end of the said rod passing through the rectangular opening in the body, a cylindrical end at the opposite end thereof, a keyway at the said end, and a projection on the said cylinder extending into the said keyway for the purpose specified. 80

4. A loading device for revolvers, comprising a body having a plurality of cartridge carrying compartments arranged in circular formation therein, a movable member centrally located in the said body with respect to the said compartments, prongs on the said member extending into the path of the cartridge chambers to normally support the cartridges, yieldable means in operative engagement with the said member to move same and carry the prongs out of the path of the cartridges, when pressure is applied to the said means, a spring actuated ring movably maintained on the body intermediate its ends, and 100 prongs on the said ring extending into the compartments for the purpose specified. 90

5. A loading device for revolvers, comprising a body having a rectangular opening centrally located at the top thereof, a cylindrical chamber below the said opening, a plurality of cartridge carrying compartments arranged radially with respect to the said opening and chamber, a cylinder movably mounted in the chamber, prongs extending from the said cylinder extending into the path of the compartments for normally supporting the cartridges, a spring pressed rod slidably mounted in the cylinder, a rectangular and twisted shank at one end of the said rod passing through the rectangular opening in the body, a cylindrical end at the opposite end thereof, a keyway at the said end, a projection on the said cylinder extending into the said keyway for the purpose specified, a spring actuated ring movably maintained on the body intermediate its ends, and 110 prongs on the said ring extending into the compartments for the purpose specified. 95

6. A loading device for revolvers comprising a body having a vertical cylindrical central chamber therein open at the bottom and provided with a rectangular opening at the top, a plurality of cartridge carrying open compartments in the said body parallel to the central chamber and arranged in circular formation about 115 same, a cylinder in the said central chamber and partially rotatable therein, prongs at the bottom of said cylinder extending into the path of the lower ends of the cartridge compartments, and spring pressed means keyed to the said cylinder 120 and passing through the rectangular opening in the body and depending below the prongs for the purpose specified. 125

7. A loading device for revolvers comprising a body having a vertical cylindrical central chamber therein open at the bottom and provided with a rectangular opening at the top, a plurality of cartridge carrying open compartments in the said body parallel to the central chamber and arranged in circular formation about same, 130 a cylinder in the said central chamber and partially rotatable therein, prongs at the bottom of said cylinder extending into the path of the lower ends of the cartridge compartments, spring 135 pressed means keyed to the said cylinder and 140 passing through the rectangular opening in the body and depending below the prongs for the purpose specified. 145

150

passing through the rectangular opening in the body and depending below the prongs for the purpose specified, a spring actuated ring movably maintained on the body intermediate its ends, 5 and prongs on the said ring extending into the compartments for the purpose specified.

8. A loading device for revolvers comprising a body having a vertical cylindrical central chamber therein open at the bottom and provided 10 with a rectangular opening at the top, a plurality of cartridge carrying open compartments in the said body parallel to the central chamber and arranged in circular formation about same, a cylinder in the said central chamber and partially rotatable therein, prongs at the bottom 15 of said cylinder extending into the path of the lower ends of the cartridge compartments, spring

pressed means keyed to the said cylinder and passing through the rectangular opening in the body and depending below the prongs for the purpose specified, and a cap removably secured to the body at the end opposite the cylinder 80 prongs.

9. A loading device for revolvers, comprising a body having a plurality of cartridge carrying compartments arranged in circular formation therein, a turntable member centrally located in the said body with respect to the said compartments for normally supporting the cartridges, and yieldable means in operative engagement with the said member to turn and move same out of the path of the cartridges when pressure 90 is applied to said means.
